UNITED STATES PATENT OFFICE.

WILLIAM A. MACK, OF NORWALK, OHIO, ASSIGNOR TO THE STANDARD SEWING MACHINE COMPANY, OF OHIO.

SHUTTLE-ACTUATING MECHANISM FOR SEWING-MACHINES.

SPECIFICATION forming part of Letters Patent No. 447,253, dated February 24, 1891.

Application filed November 14, 1888. Serial No. 290,856. (No model.)

To all whom it may concern.

Be it known that I, WILLIAM A. MACK, a citizen of the United States, residing in the city of Norwalk, in the county of Huron and 5 State of Ohio, have invented certain new and useful Improvements in Sewing-Machines of the Rotary-Shuttle Class, of which the following, taken in connection with the drawings, is a specification.

10 My invention relates to improvements in sewing-machines of the rotary-shuttle class; and it consists in the construction and arrangement of the means for operating or rotating the shuttle in a manner as will herein- 15 after be set forth in detail, and pointed out in the claims.

Referring to the drawings, Figure 1 represents a bottom view of a machine showing my improvements thereon. Fig. 2 is a sec- 20 tional view through the center of the bed and upright arm of a machine. Fig. 3 is an enlarged sectional view through the center of the driving-shaft, cam, shuttle-driver, and shuttle-race. Fig. 4 is a front or face view of 25 the shuttle and raceway.

A represents the bed-plate of a sewing-machine, and B the driving-shaft.

C is a hanger located on the underside of the bed-plate, provided with an opening through 30 which one end of the driving-shaft passes and is supported thereby. Said hanger is also provided with an extension c, extending horizontally therefrom, as more clearly shown in Figs. 2 and 3, on which a sleeve D, having a cam-surface on that side adjacent to the shuttle, is located and adjustably secured in a sta- 35 tionary position thereon by a set-screw d.

E is a shuttle-driver pivotally secured at its center on the driving-shaft B, and is pro- 40 vided with two arms or pins e e, pivotally secured at each end of the same. Said shuttle- driver is rotated by the driving-shaft B, and is given a reciprocatory movement by reason of the contact, in this instance, of the said pins 45 or arms e e back of their pivotal point of connection with said driver E with the cam face or surface of the sleeve D. This reciproca- tory movement of the shuttle-driver causes the ends of the said arms or pins e e to alter- 50 nately enter and withdraw from openings e' e', with which the shuttle G is provided, and rotate the said shuttle.

F is the shuttle-race frame, circular in form, and provided with an interior raceway, within which the said shuttle G is held and ro- 55 tated.

H is a circular plate secured in a fixed po- sition at the end of the driving-shaft B, act- ing as an intermediary support and guide be- 60 tween the shuttle-driver and shuttle for the said pins or arms e e, which pass through openings in the same.

The operation of my improved device is as follows: The shuttle is first inserted into po- sition at the front of the shuttle-frame, and 65 the ends of the pins or arms e e entered with- in the openings in said shuttle adapted for the reception of the same. The bobbin is then inserted within the shuttle. The ma- chine being put in motion, the shuttle passes 70 through the loop in the thread and the pins or arms e e alternately withdraw at the proper moment when the thread nears the same to allow it to pass without obstruction by means of the contact of said shuttle-driver with the 75 cam face or surface of the plate D.

Having thus set forth my invention, what I claim as new, and desire to secure by Let- 80 ters Patent of the United States, is—

1. In a sewing-machine, the combination, with the shuttle-race, of a shuttle provided with openings or recesses therein, a driving- 85 shaft, a shuttle-driver pivotally mounted on said shaft and provided with pivoted arms, a guide-plate for said pivoted arms, and a cam adapted to operate said shuttle-driver and arms, substantially as described, and for the purpose set forth.

2. In a sewing-machine, the combination, with a shuttle-race, of a shuttle provided with 90 openings therein, a driving-shaft and a shut- tle-driver pivotally mounted on the said driv- ing-shaft and provided with pivoted arms, a 95 guide-plate located between said driver and shuttle-race, and a stationary cam surround- ing the driving-shaft, substantially as de- scribed, and for the purpose set forth.

WILLIAM A. MACK.
